DIGITAL CLOCK

Nobuyoshi Hirosawa, Shimosuwa-machi, Japan, assignor
to Kabushiki Kaisha Sankyo Seiki Seisakusho, Shimo-
suwa-machi, Japan

Filed June 13, 1973, Ser. No. 369,615

Term of patent 14 years

Int. Cl. D10—01

U.S. Cl. D10—15

Fig. 1

Fig. 2

Fig. 3

Fig. 4

FIG. 1 is a front elevational view of a digital clock showing my new design. The rear, not shown, is substantially plain and unornamented.

FIG. 2 is a left side elevational view thereof.

FIG. 3 is a left side, top and front perspective view thereof.

FIG. 4 is a right side, bottom and front perspective view thereof.

I claim:

The ornamental design for a digital clock, as shown and described.
